US0D1063225S

(12) **United States Design Patent** (10) **Patent No.:** **US D1,063,225 S**
(45) **Date of Patent:** **** Feb. 18, 2025**

(54) **PROTECTIVE HELMET**

(71) Applicant: **OTOS WING. CO., LTD.**, Seoul (KR)

(72) Inventors: **Moon Young Huh**, Seoul (KR); **Sung Won Huh**, Seoul (KR)

(73) Assignee: **OTOS WING. CO., LTD.**, Seoul (KR)

(**) Term: **15 Years**

(21) Appl. No.: **35/514,401**

(22) Filed: **Nov. 30, 2021**

(80) **Hague Agreement Data**

Int. Filing Date: **Nov. 30, 2021**

Int. Reg. No.: **DM/219511**

Int. Reg. Date: **Nov. 30, 2021**

Int. Reg. Pub. Date: **Jun. 10, 2022**

(30) **Foreign Application Priority Data**

Jun. 7, 2021 (KR) 30-2021-0027050

(51) **LOC (15) Cl.** **02-03**

(57) **CLAIM**

The ornamental design for a protective helmet, as shown and described.

DESCRIPTION

1. Protective helmet

1.1 : Perspective

1.2 : Front

1.3 : Back

1.4 : Left

1.5 : Right

1.6 : Top

1.7 : Bottom

the design shows a protective helmet to which a face shield can be fitted; the part represented in solid lines is part of the claimed design; the dotted broken lines show the part of the

(Continued)

band that can be removed from the helmet and the fitting for the connection of a hose which form not part of the claimed design.

1 Claim, 7 Drawing Sheets
